United States Patent Office

Des. 183,411

Patented Aug. 19, 1958

183,411

SINGLE-BITTED HATCHET

Thomas J. Treteway, Seattle, Wash., assignor of one-half to Paul Bromley, Seattle, Wash.

Application August 5, 1957, Serial No. 47,232

Term of patent 14 years

(Cl. D93—4)

I claim:

The ornamental design for a single-bit hatchet, as shown.
